UNITED STATES PATENT OFFICE.

WILLIAM G. DAVIDSON, OF CHICAGO, ILLINOIS.

VISIBLE INDEX RECORD.

Application filed March 31, 1920. Serial No. 370,310.

To all whom it may concern:

Be it known that I, WILLIAM G. DAVIDSON, a citizen of the United States, and resident of Chicago, in the county of Cook and State 5 of Illinois, have invented a new and useful Improvement in Visible Index Records, of which the following is a specification.

This invention relates to visible index records, such as card index systems and the 10 like.

The object of the invention is to provide a visible index record of the type specified, which shall be simple in construction and operation and which is adapted to contain a 15 relatively very large number of individual records in a given space as compared with any record of this type of which I have any knowledge.

In accordance with my invention, my im- 20 proved visible index record comprises a base plate secured to which, by a flexible connection, is a plurality of supports, said sup- ports being arranged so that they will over- lap, the relation being such that a portion 25 of the free edge of each of said hinged sup- ports will be exposed when said hinged sup- ports lie in normal flatwise positions, each 30 of said hinged supports being provided on both sides, adjacent to its hinged edge, with pockets adapted to receive the edges of cards, the relation being such that when a card is 35 inserted into said pockets, respectively, it will lie flat against said hinged support with its outer edge substantially even with the 40 outer edge of the hinged support to which it is thus removably attached, whereby a sufficient portion of the free edge of said card will be exposed to receive a name, address or other identifying data. Also, to 45 provide for making entries on both sides 50 of cards carried by said hinged supports, said cards, respectively, are constructed to fold at the edges of the pockets in which 55 they are secured, so that they may be folded over or down to expose the sides thereof 60 which normally rest in contact with the sur- faces of said hinged supports.

The invention also comprises the various 65 other features, combinations of features and details of construction hereinafter described and claimed.

In the accompanying drawings, in which 70 my invention is fully illustrated,

Figure 1 is a face or plan view of a visi- 75 ble index record of my invention showing hinged supports turned in opposite direc-

tions to expose opposite sides thereof, re- spectively.

Figure 2 is an enlarged fragmentary side view thereof.

Figure 3 is a fragmentary view substan- 60 tially like Fig. 1, showing one of the cards carried by a hinged support, turned back to expose the reverse side thereof which normally lies flat against said hinged support.

Figure 4 is an enlarged sectional view 65 on the line 4—4 of Fig. 1; and

Figure 5 is an enlarged fragmentary view 70 illustrating the construction of the pockets on the hinged supports which carry the index cards.

Referring now to the drawings, 1 designates a base plate, which will preferably be made of heavy binder's board, but may be made of any other suitable material.

Secured to said base plate 1 by means of 75 a flexible connection so that they may be turned to lie with either side thereof ex- posed, is a plurality of what appropriately may be designated hinged supports 2. In 80 practice, I contemplate making said hinged supports of a grade of wrapping paper suffi- ciently heavy and stiff to retain its shape, the attached ends of which are gummed or pasted to said base plate, said hinged sup- ports being also preferably scored or perfo- 85 rated adjacent to their hinges, as shown at 3, to provide for conveniently turning them to expose both sides thereof.

Said hinged supports are arranged in 90 overlapping series, the relation being such that a portion of the free edge of each of said hinged supports, say from one-quarter to five-sixteenths of an inch, will be exposed when said hinged supports lie in normal 95 flatwise position.

Formed on both sides of said hinged sup- ports adjacent to their attached edges are 100 pockets 4 adapted to receive the edges of cards 5, thereby providing for removably securing cards to both sides of said hinged supports.

As shown, said pockets are formed by 105 strips of paper 6, the edges of which adja- cent to the hinges of the hinged supports 2 are pasted or otherwise rigidly secured to said hinged supports, leaving the opposite edges of said strips free, and the lateral edges of said strips corresponding to the lateral edges of the hinged supports 2, being likewise rigidly secured to said hinged sup- ports, convenient means for this purpose 110

consisting of clips 7 applied to opposite ends of the strips 6 secured to opposite sides of each hinged support 2, the relation being such that the unattached portions of said strips 6 will lie flat against the sides of the hinged supports 2.

The cards 5 are of such size that they may be inserted into the pocket formed by the strips 6 and will extend substantially even with the free edges of the hinged supports 2, whereby from one-quarter to five-sixteenths of an inch of each card will be exposed when said hinged supports lie in normal flatwise position, such exposed portions of said cards being designed to receive a name, address or other identifying data.

The cards 5 are constructed and arranged to fold on lines parallel with and adjacent to the edges thereof designed to be inserted into the pockets 4, the relation being such that said lines of fold will be even with or a little outside of the edges of the strips 6 forming said pockets, thus providing for folding said cards over to expose the reverse sides thereof, that is, the sides which normally lie in contact with the surfaces of the hinged supports 2, thus providing for making or examining entries on the reverse sides of said cards without removing them from the pockets in which they are secured. To provide for conveniently folding said cards on desired lines, they are preferably scored or perforated along the lines of fold, as shown at 8.

In practice, the names of the subjects to which entries to be made on the cards 5 relate, as the names of individuals, different kinds of merchandise or other articles or subjects, are printed on the portions of said cards which will be exposed when the hinged supports 2 lie in normal flatwise position, together with the addresses of such individuals or other identifying data, the cards with the identification entries arranged in alphabetical order, being then inserted into the pockets 6 on the hinged supports 2, cards containing names beginning with the first letters of the alphabet, as from A to M, being secured to what, for purposes of convenient reference, may be referred to as the front sides of said hinged supports, and those containing entries beginning with the last letters of the alphabet being secured to the opposite or rear sides of said hinged supports, and said indexes being printed in such manner that when said hinged supports are turned in position to expose the cards secured thereto, the writing on all of said cards will be right side up with reference to a predetermined position of the base plate 1. Thus, with the arrangement shown in the drawings, the entries on the rear side of said cards will be upside down as regards the entries on the front sides.

If, however, the hinged supports 2 are se-

cured to the base plate 1 so as to turn like the leaves of a book, the printed matter and entries on all of the cards would be right side up.

The base plate 1 is made sufficiently long 70 so that the hinged supports 2 will rest in contact therewith when turned to expose the cards secured to either or both sides thereof.

In the preferable construction shown, a cover section 9 is hinged to one edge of the 75 base plate in such manner that it may be folded over the base plate 1 and the hinged supports 2 carrying the cards 5 secured thereto, thus protecting the record portion of the device from injury when not in use, 80 and particularly when being handled or shipped.

Where the section 9 attached to the base plate 1 merely forms a cover for said base plate and the hinged supports carried thereby, it may be made considerably lighter than said base plate, but my invention contemplates equally making it of material of the same kind and character as the base plate 1 and utilizing it to carry hinged supports 90 2 and cards 5 in the same manner as the base plate 1, thereby doubling the capacity of the record. As the hinged supports, pockets and cards will be in all respects the same as herein shown and described in connection with the base plate 1, any person of ordinary skill in the art can readily reproduce them in connection with the cover portion 9 and the same need not, therefore, be shown or described in detail, as to do so 95 would merely result in needless repetition and in unduly extending the specification without adding clearness thereto.

I claim:—

1. In a visible index record, the combination of a base plate, a plurality of hinged supports attached thereto, pockets formed on both sides of said hinged supports adjacent to their points of attachment to said base plate adapted to receive the edges of record cards, said hinged supports being arranged in series and the relation being such that when said hinged supports lie in normal flatwise position, a portion of the free edge of each of the cards on the exposed sides of said hinged supports will be visible, substantially as described. 105

2. In a visible index record, the combination of a base plate, a plurality of hinged supports attached thereto, pockets on said hinged supports adjacent to their points of attachment to said base plate adapted to receive the edges of record cards, said hinged supports being arranged in series and the relation being such that when said hinged supports lie in normal flatwise position, a portion of the free edge of each of said cards adapted to receive index entries will be visible, said record cards being constructed and arranged to fold over to expose the re- 110 115 120 125 130

verse sides thereof, substantially as described.

3. In a visible index record, the combination of a base plate, a plurality of hinged supports attached thereto, pockets on said hinged supports adjacent to their points of attachment to said base plate adapted to receive the edges of record cards, said hinged supports being arranged in series and the relation being such that when said hinged supports lie in normal flatwise position a portion of the free edge of each of said cards adapted to receive index entries, will be visible, the pockets on said hinged supports consisting of strips of flexible material, the edges of which adjacent to the hinges of said hinged supports are gummed or otherwise attached to said hinged supports and the opposite edges of which are free, and means for attaching the lateral margins of the free edges of said flexible strips to said hinged supports, substantially as described.

4. In a visible index record, the combina-

tion of a base plate, a plurality of hinged supports attached thereto, pockets on said hinged supports adjacent to their points of attachment to said base plate adapted to receive the edges of record cards, said hinged supports being arranged in series and the relation being such that when said hinged supports lie in normal flatwise position a portion of the free edge of each of said cards adapted to receive index entries, will be visible, the pockets on said hinged supports consisting of strips of flexible material, the edges of which adjacent to the hinges of said hinged supports are gummed or otherwise attached to said hinged supports and the opposite edges of which are free, and clips for attaching the lateral margins of the free edges of said flexible strips to said hinged supports, substantially as described.

In testimony that I claim the foregoing as my invention, I affix my signature this 19th day of March, 1920.

WM. G. DAVIDSON.
